(57) **CLAIM**

The ornamental design for a connector receptacle, as shown and described.

DESCRIPTION

FIG. 1 is a front perspective view of a connector receptacle showing our new design;

FIG. 2 is a top view thereof;

FIG. 3 is a right side view thereof;

FIG. 4 is a left side view thereof;

FIG. 5 is a front view thereof;

FIG. 6 is a rear view thereof;

FIG. 7 is a front perspective view of the connector receptacle of FIGS. 1-6 showing our new design including an alternative broken line convention;

FIG. 8 is a top view thereof;

FIG. 9 is a right side view thereof;

FIG. 10 is a left side view thereof;

FIG. 11 is a front view thereof;

FIG. 12 is a rear view thereof; and,

FIG. 13 is a bottom view thereof.

The Dash-Dot broken line adjacent to the shaded area represents a boundary of the design that forms no part of the claimed design. The broken line showing of the various unshaded elements of the connector receptacle represents subject matter that forms no part of the claimed design.
